(57) **CLAIM**

I claim, the ornamental design for a syringe plunger, as shown and described.

DESCRIPTION

FIG. 1 is a perspective view of a syringe plunger, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view taken along line 8-8 of FIG. 2.

The broken lines shown in the drawings depict portions of the syringe plunger which form no part of the claimed design.
